WRENCH

Adam E. Johnson, Naugatuck, Conn.

Application June 18, 1938, Serial No. 214,481

1 Claim. (Cl. 81—89)

This invention relates to wrenches, and more particularly to a wrench having a pair of relatively slideable jaws and improved means for rapidly opening and closing said jaw, and for adjusting them to fit different sizes of nuts or other articles to be gripped thereby.

One object of this invention is to provide a wrench of the above type, in which one of said jaws is provided with a rack which meshes with a swingable gear segment on a jaw closing lever, and in which said lever is operated by a toggle action, whereby a relatively powerful grip will be obtained upon the article disposed between the jaws.

A still further object is to provide a wrench of the above type which will be simple in construction, inexpensive to manufacture, readily manipulated, compact, ornamental in appearance, and very efficient and durable in use.

With these and other objects in view there has been illustrated on the accompanying drawings a form in which the invention may be conveniently embodied in practice.

In the drawings:

Fig. 1 is a perspective view of a wrench embodying the principles and features of this invention, a part of the operating lever being broken away to disclose the interior mechanism.

Fig. 2 is a longitudinal sectional view of the same, the gear segment being shown out of engagement with the rack to permit the rapid adjustment of the jaws to an article to be gripped thereby.

Fig. 3 is a longitudinal sectional view similar to Fig. 2, but showing the jaws thereof in article gripping position.

Fig. 4 is a cross-sectional view taken on the line 4—4 of Fig. 3.

Fig. 5 is a cross-sectional view taken on the line 5—5 of Fig. 3.

Referring now to the drawings wherein like reference characters designate like parts throughout the several views, the numerals 10 and 11 indicate a pair of jaws between which an article, such as a nut 12, may be gripped. The jaw 10 is herein shown formed integral with a shank 13 which is substantially rectangular in cross-section, and the jaw 11 is herein shown formed integral with a sleeve 14 which is adapted to slide on said shank 13. The sleeve 14 has a longitudinally extending opening 15 fitted over the shank 13, the latter being of sufficient length to extend considerably beyond each end of the sleeve 14. The shank 13 is provided on its upper edge with a plurality of gear rack teeth 16,

which are disposed intermediate its ends. A stop pin 17 passes through the shank 13 and is engaged by the rear end of the sleeve 14 to limit the rearward movement of the latter on the shank 13. The end of the shank 13 opposite from the jaw 10 comprises a lever handle 18 for the wrench and has a plurality of finger grooves 19 extending across the under surface thereof to facilitate manually gripping the same.

The sleeve 14 is provided with a pair of spaced apart ears 20 and 21 which are straddled by wings 22 and 23 formed on the lower end of a sheet metal handle 24 which is generally U-shaped in cross-section. A pin 25 passes through the ears 20, 21 and the wings 22, 23 to pivotally connect the handle 24 to the sleeve 14. A wire cutting notch 26 is provided in the arm 23 of the handle 24 to cooperate with a similar notch 27 formed in the ear 21 of the sleeve 14, whereby wire or the like may be cut when the handle is rotated upon the pivot pin 25.

A gear-toothed segment 28 is pivotally connected to the handle 24 by a pin 29. The axis of the pin 29 is disposed eccentric with respect to the center of the arc of the gear segment 28, whereby the teeth 30 will lie substantially tangent with the rack teeth 16 when the handles 18 and 24 are pressed together, as shown in Fig. 1.

The front edge 31 of the segment 28 is adapted to engage the rear edges 32 and 33 of the ears 20 and 21, respectively, to limit the forward swinging of the gear segment 28 upon the pin 29, when the handles 18 and 24 are separated and to thus insure the unmeshing of the segment teeth 30 from the rack teeth 16, as shown in Fig. 2.

A wire spring 34, coiled about the pin 29 in a U-shaped recess 35 formed in the gear segment 28, has one of its ends 36 in engagement with said gear segment 28, and its other end 37 in engagement with the underside of the handle 24. The spring 34 is tensioned to constantly urge the gear segment clockwise, so as to cause the edge 31 to engage the rear edges 32 and 33 of the ears 20 and 21.

Operation

When it is desired to employ the wrench to grip an article, such as the nut 12, the user will raise the handle 24 away from the handle 18 into the position shown in Fig. 2, the spring 34 holding the front edge 31 of said segment against the edges 32 and 33 of the ears 20 and 21. The teeth 30 of the segment 28 are thereby unmeshed from the teeth 16 on the handle 18, and the

sleeve 14 with its jaw 11 may be then manually slid forwardly along the shank 13 to move the jaw 11 into engagement with an arcle, such as the nut 12, which is seated on the jaw 10.

5 The handles 18 and 24 will then be pressed together, and the segment 28 will be caused to move about the pin 25, due to it being carried by the handle 24 until the teeth 30 of said segment 28 come into mesh with the teeth 16 on the 10 shank 13. Continued pressure upon the handles 18 and 24 will force the pin 29 downwardly, and by means of the toggle action, will exert a powerful force upon the meshed teeth 16 and 30 and the pivot pin 25. This force will then act through 15 the sleeve 14 and the shank 13 to cause the jaws 10 and 11 to powerfully grip the nut 12, as indicated in Fig. 3.

When the handles 18 and 24 are released, they 20 will separate slightly, as shown in Fig. 2, permitting the wrench to be manually rotated rearwardly about the nut 12, or other article being acted upon, by a sort of "ratchet" action and to dispose the jaws 10 and 11 on the next succeeding opposite pair of faces of the nut. During this 25 action, the sleeve 14 will automatically retract sufficiently to permit the jaws 10 and 11 to ride over the corners of the nut 12, as indicated in dotted lines in Fig. 3. Moreover, the teeth 16 and 30 will not become unmeshed, but will be held in 30 mesh by the pressure of the spring 34 upon the segment 28.

It will be understood that the portion of the 35 handle 24 between the pins 25 and 29 constitutes one link of the toggle, and that the segment 28

constitutes the other link of the toggle, said links being acted upon at their common pivot pin 29 by pressure imposed by the handle 24 to spread their respective remote ends.

While there has been disclosed in this specification one form in which the invention may be embodied in practice, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claim.

Having thus fully described the invention, what 15 is claimed as new and for which it is desired to secure Letters Patent, is:

In a wrench, a first jaw having a shank forming a front handle, a sleeve having a jaw opposing said first jaw and being slidably mounted on said shank, said shank having a plurality of rack teeth formed thereon, a second handle pivoted to said sleeve above the upper surface of said shank, a curved gear toothed segment adapted to mesh with said rack teeth and pivoted to said second 25 handle at a point distant from the handle-sleeve pivot, and spring means reacting between said second handle and said segment to urge said segment teeth into mesh with the teeth on said shank, said gear segment being caused to rotate about its 30 pivot and roll along said rack teeth when said handles are pressed toward each other.

ADAM E. JOHNSON.
